(57) **CLAIM**

The ornamental design for a tree guard rail, as shown and described.

DESCRIPTION

FIG. 1 is a perspective view of a tree guard rail.
FIG. 2 is a front view of the embodiment of FIG. 1.
FIG. 3 is a top view of the embodiment of FIG. 1.
FIG. 4 is a side view of the embodiment of FIG. 1; and,
FIG. 5 shows the embodiment of FIG. 1 in the context of use
with a portion of a tree guard.
The broken lines are for illustrative purposes only and form
no part of the claimed design.
